UNITED STATES PATENT OFFICE.

ANDREAS RADOVANOVIC, OF ZURICH, SWITZERLAND.

PUMP.

SPECIFICATION forming part of Letters Patent No. 722,142, dated March 3, 1903.

Application filed November 14, 1902. Serial No. 131,427. (No model.)

To all whom it may concern:

Be it known that I, ANDREAS RADOVANOVIC, a subject of the Emperor of Austria-Hungary, residing at Zurich, in the Republic of Switzerland, have invented certain new and useful Improvements in Pumps, of which the following is a specification.

This invention relates to pumps, and according thereto a pump is provided with apparatus which is adapted before the commencement of the suction-stroke of the pump to generate below the suction-valve a hydraulic pressure that will facilitate the opening of the suction-valve and the flow into the pump-barrel of the liquid to be conveyed, and so prevent the disruption of the column of liquid during the suction-stroke, and before the commencement of the delivery-stroke to generate under the suction-valve a steadily-increasing hydraulic pressure which just before the change of stroke will become nearly equal to that exerted by the plunger of the pump during its delivery-stroke, so that the slight excess of pressure in the barrel which will thereupon ensue will cause the suction-valve to be closed without shock.

In the accompanying drawings, forming a part of this specification, Figure 1 is a sectional view of a pump constructed in accordance with my invention; Fig. 2, a detail sectional view of the piston *v* shown in Fig. 1; Fig. 3, a sectional view illustrating a modified construction of chamber *m* and piston *v*; Fig. 4, another modification wherein two valves are employed in place of the piston *v*; Fig. 5, a further modification; Fig. 6, a diagrammatic view, the pump being shown in elevation, of a modified construction for operating the piston *v*; Fig. 7, another modified arrangement of the invention, and Fig. 8 a detail sectional view of the piston shown in Fig. 7.

Under the suction-valve *s*, Fig. 1, there is a chamber *m*, which is separated from the suction air-chamber and suction-pipe *w* by means of a contracted portion *c*, in which a piston *v* is moved by mechanism resembling valve-gear. A suitable clearance *p* is left between *v* and *c*. This arrangement operates as follows: When, as shown in Fig. 1, the pump is at the commencement of its suction-stroke and its plunger is at the dead-point, the

eccentric *e*, which operates the piston *v* by means of the linkwork *e'*, has already passed beyond its dead-point and tends to move the piston *v* upward, and thereby force liquid from the chamber *m* into the chamber *w* through the clearance *p*. Owing, however, to the throttling of the liquid, there arises in the chamber *m* a hydraulic pressure, which on the commencement of the suction-stroke of the pump at once opens the suction-valve and drives the liquid into the pump. When on further movement the piston *v* has left the contraction *c*, as shown by dotted lines, the hydraulic pressure in the chamber *m* ceases and the pump then draws its supply directly from the chamber *w*. In order that the hydraulic pressure produced by the piston *v* may be gradually merged into that produced directly by the suction of the pump, the contraction *c* is so formed as gradually to augment the clearance between *c* and *v*. The piston *v*, as shown in Fig. 2, is provided with a flap-valve *v'*, opening upward. The liquid passes through this valve from *w* to *m* without throttling both during the suction-stroke of the pump and during the downward movement of the piston *v*. As the plunger toward the end of its suction-stroke approaches its extreme outward position the piston *v* is again moved upward into the contracted portion *c*. This may be effected by causing the shaft which actuates the eccentric *e* to make two revolutions for each revolution of the pump-shaft which operates the plunger, or the mechanism shown in Fig. 6 may be employed, wherein each revolution of the shaft or of the eccentric *e* causes the lever *e''* to make two oscillations. Through the entry of the piston *v* into the chamber *m* there is again generated in this chamber a hydraulic pressure, which as long as the suction-stroke continues is transmitted to the pump-barrel. By adopting suitable proportions for the cross-sections of the piston *v* and the clearance *p* in relation to the speed of the piston the pressure generated by the piston *v* at the dead-point of the pump-plunger can be increased until it is nearly equal to that exerted by the plunger during its delivery-stroke. Now at the instant that the plunger changes its direction of movement and commences its delivery-stroke the hydraulic pressure pro-

duced in the chamber m by the piston v simultaneously begins slowly to diminish, as it may be caused to do by giving a suitable form to the contraction c or the piston v , and the 5 suction-valve will be closed by a very slight excess of pressure on its upper side, and consequently without shock. A special valve-gear may, however, in some cases be provided to effect at this instant the closure of the 10 valve.

Instead of doubling the rate of rotation of the shaft which actuates the piston v or of employing the mechanism shown in Fig. 6 the piston v may, as shown in Fig. 7, be formed 15 as a hollow double-beat valve, which makes the same number of strokes as the pump-plunger and can be driven directly from the pump-shaft, but which during both its upward and its downward movement generates 20 a hydraulic pressure in the chamber m . The piston v when formed as just described is provided with a valve v' , opening upward, analogous to the valve v' already referred to with 25 reference to and shown in Fig. 2, and a second valve v'' , through which the liquid can enter into the chamber m' , is located either on the casing, Fig. 7, or on the piston v , Fig. 8. The arrows x and y show the direction of the movement of the piston v prior to the 30 commencement of the suction-stroke and the delivery-stroke, respectively. The arrows x' and y' show the corresponding directions of flow of the liquid. The piston v during its movement in the direction of the arrow x operates with the difference of cross-section corresponding to the diameters d' and d and generates a hydraulic pressure both in the chamber m and also in the chamber m' . During 35 the movement of the piston v in the direction 40 of the arrow y it works with a surface corresponding to d and generates hydraulic pressure only in the chamber m . In other respects the method of operation of this double-acting piston v is just the same as that of the 45 single-action arrangement, which runs at twice the speed.

Fig. 3 shows an arrangement wherein the piston v is adapted to be oscillated and has its valve v' formed as a flap on its side toward 50 the suction-valve s , as shown by dotted lines. In the example shown in Fig. 4 the valve v' is arranged separately from the piston v .

Fig. 5 shows a modification wherein the piston v is formed as a plunger and the valve 55 v' , which, as in the example shown in Fig. 4, is separate from the piston v , does not even when in its lowest position entirely close, but leaves a clearance p , which in this case will

be constant and through which the liquid forced by the piston v from m to w escapes. 60 After the hydraulic pressure in m has ceased, the pump on the acceleration of its plunger draws liquid directly through the valve v' .

In order to prevent excessive rise of pressure in the chamber m , a suitably-loaded 65 safety-valve t , opening from the chamber m into the chamber w , may be provided both in the arrangement just referred to and in those previously described.

The piston v may be operated from the 70 pump-shaft by any convenient mechanical or hydraulic means, and the position and the direction of movement of the piston v in relation to the axis of the suction-valve s can be arranged as desired. 75

The piston v and the aperture corresponding thereto in the contracted portion c may be of any desired form. For an oscillating piston, for instance, the rectangular form 80 will be the most suitable.

The improvements herein described are applicable to pumps and pump-valves of all kinds. 85

I claim—

1. In a pump, a pump-cylinder, a pump-piston in said cylinder, means for operating said piston, a valve opening into said cylinder, a chamber adjacent to said valve, a compression-valve in said chamber, and means for operating said compression-valve immediately before the beginning and the end of the stroke of said pump-piston. 90

2. In a pump, a pump-cylinder, a pump-piston in said cylinder, a valve opening into said cylinder, a chamber adjacent to said valve, a compression-valve in said chamber, an eccentric for operating said pump-piston, and an eccentric for operating said compression-valve immediately before the beginning and the end of the stroke of said pump-piston. 100

3. In a pump, a pump-cylinder, a pump-piston in said cylinder, means for operating said piston, a valve opening into said cylinder, a chamber adjacent to said valve, and means for creating hydrostatic pressure in said chamber immediately before the beginning and the end of the stroke of said pump-piston. 105

In testimony whereof I have hereunto set my hand in presence of two subscribing witnesses.

ANDREAS RADOVANOVIC.
